COMBINED PLAYING CARD HOLDER AND ASH
TRAY OR SIMILAR ARTICLE

Ralph E. Burchstead and Robert Peterson, Beverly, Mass.

Application May 27, 1954, Serial No. 30,702

Term of patent 14 years

(Cl. D34—13)

Fig. 1

Fig. 2

Fig. 1 is a perspective view of a combined playing card holder and ash tray or similar article, showing our new design.

Fig. 2 is a side elevational view.

The two playing cards do not constitute part of the article and are shown for illustrative purposes only.

We claim:

The ornamental design for a combined playing card holder and ash tray or similar article, as shown and described.
